INVENTOR
NELLIE EICHEL

BY *E. Hoffman*
ATTORNEY

UNITED STATES PATENT OFFICE.

NELLIE EICHEL, OF ST. LOUIS, MISSOURI.

BANDEAU.

Application filed August 21, 1925. Serial No. 51,565.

My invention relates to a bandeau or pad adapted to be attached either directly to the material of a hat or to the lining thereof. Bandeaux embodying a metallic band or 5 wire ring have heretofore been used extensively in connection with hats of stiff material. Such bandeaux, however, cannot be successfully used in hats of felt or other soft material such, for example, as those 10 known as "sport" hats.

The principal object of the present invention is to so construct a bandeau that it may, with equal facility and practical success, be applied either to soft or stiff hats.

15 In the accompanying drawings, which illustrate one form of bandeau made in accordance with my invention, Figure 1 is a cross section of a hat to which my bandeau is applied, one side of the bandeau being 20 in section and the other in elevation; Figure 2 is a fragmentary face view of a portion of the bandeau; Figure 3 is an enlarged cross section; and Figure 4 is a detail view of one of the fastening devices.

25 The hat, indicated at 5, to which my bandeau is applied, may be of any suitable shape and material. In the drawings I have shown a soft felt hat of the "sport" type. While, as hereinbefore stated, the bandeau 30 may be attached directly to the material of the hat, I have shown the hat as provided with a lining 6, to which the attachment is made.

The bandeau is formed from a strip of 35 textile fabric, such as silk, which is folded upon itself, as shown in Figure 3, so as to form an inner or facing layer 7, a backing layer 8, and at the upper edge an outer or overlapping layer 9. These three layers are 40 fastened together by a row of stitching 10 to form a pocket to receive a draw string or tape 11. Arranged at the lower edge of the device between the facing layer 7 and the backing layer 8 are inner and outer 45 padding strips 12 and 13 respectively. The inner padding strip 12 is formed of some soft material while the outer strip 13 is of

stiff material, such as buckram, which will give the device the necessary rigidity in an edgewise direction without materially decreasing its flexibility laterally. Supported by the strip 13 are the fastening devices which, in the form shown, consist of hook shaped wire members each comprising a body portion 14 adapted to pass around or 50 through the buckram strip, and an upwardly projecting recurved point 15.

In applying my bandeau the points 15 of the fastening members are forced upwardly either into the material of the hat, or if the 55 hat is lined, into the material of the lining, as shown in the drawings, the recurved form of the points causing them to pass back out of the material, as shown in Figure 3. As the points of the hooks project upwardly the 60 weight of the hat when worn will tend to hold the pierced material against the bottom of the hooks instead of tending to hold the point out of the material as would be the case if the fasteners were reversed. The 65 shape of the point also tends to prevent the withdrawal of the hooks, and further facilitates the bending of the point toward the body after the hook is in position thus clamping a portion of the material between 70 the two parts. The draw string 11 enables the upper edge of the bandeau to be accurately adjusted to the size of the hat.

Having fully described my invention, what I claim as new and desire to secure by Letters Patent of the United States is:

A pliable non-resilient bandeau for hats, comprising a casing of pliable textile material, a pliable strip of material within the casing and having substantial rigidity in the 85 direction of its width, and pin members passing through one wall of the casing and each secured to the strip at two points one above the other, the hat engaging portions of the pins extending upwardly adjacent to 90 the outer face of the casing.

In testimony whereof, I hereunto affix my signature, this 19th day of August, 1925.

NELLIE EICHEL.
